UNITED STATES PATENT OFFICE.

GEORGE W. N. YOST, OF NEW YORK, N. Y., ASSIGNOR TO THE AMERICAN WRITING MACHINE COMPANY, OF NEW YORK.

TYPE-WRITING MACHINE.

SPECIFICATION forming part of Letters Patent No. 336,614, dated February 23, 1886.

Application filed May 16, 1882. Serial No. 61,548. (No model.)

To all whom it may concern:

Be it known that I, GEORGE W. N. YOST, a citizen of the United States, residing in the city of New York, State of New York, have 5 invented certain new and useful Improvements in Type-Writing Machines, of which the following is a specification.

My invention relates to improvements in type-writing machines in which a series of 10 pivoted type-levers are operated by means of finger-keys in connection with key-levers and connecting-rods.

The objects of my improvements are to unite each finger-key to its lever by simple means, and at the same time retain 15 permanently their relative position after they are once united, and to provide the letters or indices placed in the top of finger-keys with concave glass covers, for the purpose herein- 20 after stated.

Heretofore finger-keys have been constructed with a strap passing directly around the key-lever or a portion thereof. Others have been made with a rectangular stem mortised 25 in its lower end so as to straddle the key-lever, with a pin driven transversely to keep them united. Finger-keys thus constructed had no guides to retain them vertically, but in many machines as now constructed guides are necessary, as long stem-keys are used in such 30 machines. The upper part of the strap or clasp secured upon key-levers has been perforated vertically, and its interiorscrew-tapped to receive the lower end of the stem of the finger-key, upon which a screw-thread has 35 been cut. One objection to this mode of fastening is that the finger-keys are liable to turn accidentally or gradually within their support, and the letters or indices upon them become 40 out of line or inclined at various angles.

Finger-keys have been provided with characters engraved or pasted within concave tops, but these characters have been left uncovered and liable to be easily defaced.

45 The objects of my invention are to remedy these defects by the mechanism illustrated in the accompanying drawings, in which—

Figure 1 represents in perspective a type-writer finger-key having its stem united to the

key-lever thereof. Fig. 2 represents the same 5c in vertical section, but upon a larger scale. Fig. 3 represents a side view of the connecting-link used to unite the finger-key to the key-lever strap. Fig. 4 is a perspective view of the same link.

55 In the drawings, A represents a type-writer key-lever, generally made of a strip of wood, around which is secured a strap, a, of sheet metal, as follows: The strap is of such length as to form two ears, a', extending above the 60 top edge of the key-lever, and at a point immediately above said top edge there is a tongue, a'', cut into and from the metal of one or both ears a', and said tongue is bent over and pressed in close contact with the upper edge 65 of the key-lever, retaining said strap permanently in position thereon. In the ears of said strap is pivoted a link, b, by means of a rivet, c, passing therethrough. This link b is nearly rectangular, and is formed of springy 70 sheet metal, the thickness of which is about equal to that of the key-lever or to the diameter of the stem d of the finger-key. In said link b a round hole, b', is made to receive the rivet c, and also at a short distance 75 above it a rectangular opening, b''. Above said opening b'' the metal of the link is filed away or removed from its two sides to form a thin partition, b'', between the two edges b' of the link, and a saw-cut, b'', is run longitudinally through this partition, to allow the two edges b' of the link to be sprung toward each other at their upper end and form a spring- 80 clasp, to firmly retain the finger-key stem d. The latter having its lower end slotted longitudinally, its branches d' can be made to straddle the thin partition b'' of the link, and rest against the edges or branches b' of said link. The inner sides of the branches b' are preferably beveled in a dovetail form, as shown in 85 Fig. 4, to conform as nearly as possible to the cylindrical form of finger-key stems, and prevent the parts becoming accidentally disconnected after having been placed together in position. This link b differs in many practical features from another link made by me for the same purpose, and presented in another 90 application for patent.

The type-writing machines upon which these stem-finger keys are used are generally provided with six parallel bars, E, secured to the sides of the frame, each having a series of 5 perforations, e, to act as guides and side-supports for the finger-keys. The space between the key-levers and guide-bars E is generally too small for the passage of the constructor's fingers, to drive a pin or rivet; hence the 10 finger-key has to be secured to its key-lever by passing it through one of the small guide-perforations e. This I accomplish in an instant by simply pushing the finger-key stems over and astride of the thin partition b³, between 15 the sprung branches b⁴ of the connecting-link.

The finger-key D is made of a bottom metallic disk, D', to which the stem d is secured, a disk, D², of enameled cloth, leather, or other suitable semi-elastic material having characters or indices printed thereon, a concave cover of glass, D³, having its concavity upward, and its bottom recessed to prevent abrasion of the indices, and a cylinder, D⁴, of thin metal, having its top and bottom edges 25 so spun or bent in as to unite the parts D', D², and D³ securely together.

It is found that by giving a curve to the glass D³, as shown, it will resist pressure without breaking better than a flat glass, and there 30 is no rattling of the parts forming the finger-key, the convex form of the glass top facilitating also the reading of the characters thereunder.

Having now fully described my invention, 35 I claim—

1. The combination of a type-writer key-lever, a strap provided with a tongue, a², adapted to press upon said key-lever, the stem of a finger-key split lengthwise in its lower end, and a connecting-link provided with a 45 partition, b³, and a split, b⁵, therein, and springy branches b⁴, substantially as and for the purpose described.

2. The combination of a type-writer key-lever, a strap secured to said lever, the stem 45 of a finger-key having its lower end split lengthwise, and a connecting-link provided with a central partition split lengthwise, and springy branches carrying the two ends of said split partition, substantially as and for 50 the purpose set forth.

3. The combination of the cylindrical stem of a finger-key, a disk, D', secured to the end thereof, and a disk, D², having characters printed thereon, with a concave glass cover, 55 D³, having its bottom recessed, and a cylinder, D⁴, having its edges turned in, substantially as and for the purpose described.

4. The combination of a type-writer key-lever, a strap secured to said lever, the stem 60 of a finger-key, and a connecting-link having two springy branches, b⁴, adapted to clasp tightly the stem of a finger-key, substantially as and for the purpose set forth.

GEORGE W. N. YOST.
